UNITED STATES PATENT OFFICE.

ROY M. BROWN, OF WILMINGTON, OHIO.

BAND-BRAKE.

1,141,035.

Specification of Letters Patent.

Patented May 25, 1915.

Application filed April 9, 1914. Serial No. 830,786.

To all whom it may concern:

Be it known that I, Roy M. Brown, a citizen of the United States, residing at Wilmington in the county of Clinton and State of Ohio, have invented certain new and useful Improvements in Band-Brakes, of which the following is a specification.

My invention pertains to the improvement of band brakes and particularly to this type of structure used in connection with the transmission mechanism of the planetary type of motor vehicles. In its broadest sense my invention is applicable to any rotating drum operating in connection with a brake band. This type of mechanism when used in connection with motor vehicles must necessarily be subjected to considerable wear; and it has been found that one corner of the stationary end of the brake band inevitably wears more than the remaining portion. As a result, when the brake band is applied, the worn corner has the tendency to maintain its engagement with the rotating drum and as a result a large portion of the band is out of engagement. This is an unnatural position for the brake band with relation to its drum and continued rotation of the drum will in turn cause the band to grip itself, but this is usually accomplished after a considerable chatter of the band. As a result, when this structure is used in connection with a transmission mechanism of a motor vehicle, the gripping effect will be uncertain and the chatter causes a jerky motion of the vehicle. I aim particularly to provide a structure for overcoming this with adjustments so that the band may be made to operate smoothly no matter what amount it may be worn.

The preferred embodiment of my invention is shown in the accompanying drawings, in which similar characters of reference designate corresponding parts, and in which:

Figure 1 is a side elevation of my structure shown in connection with a rotatable drum, Fig. 2 is an inside end view of one of the end members of the brake band, showing my invention in connection therewith, Fig. 3 is a central vertical section taken on line 3-3 of Fig. 2, and Fig. 4 is a section taken on line 4-4 of Fig. 3 and looking in the direction of the arrows.

In the drawings, I have shown at 1 any type of drum rotatable about a center 2, it being understood that my invention is applicable to brake bands in general, no matter to what use the drum may be put. Encircling this drum, there is a brake band 3 carrying end members 4 and 5 upon its two ends respectively. If this band is adapted to brake with the drum, it is essential that one of the end members should remain stationary, while the other is movable and I have shown the member 5 as a stationary member, while the member 4 is adapted to be movable. This movable member is operatively connected, as will be hereinafter described, to a pull rod 6, which pull rod passes through the member 5 in order that it may be held stationary by abutting a stop 7. This stop may be in the nature of a casting surrounding the transmission mechanism if the device is used in connection with motor vehicles, or may be any other type of stop. The band is normally held in release position by means of the coil spring 8 encircling the pull rod 6 and bearing against the end members 4 and 5.

Both of the end members 4 and 5 are provided with outwardly extending ears 9 and these ears are slotted as is shown at 10, in order to accommodate the rod 6, which rod is prevented from disengaging itself from the movable end member 4 by means of the slot 11 screwed on to the threaded portion 12. The slot in the end member 4 may have an open upper portion or not, as is desired, but the stationary end member 5 is shown as having its upper end open, but normally closed by means of the cover piece 13, which latter is securely held in the position shown by means of the screws 14. It is to be understood that the rod 6 also passes through the slot 10 in the stationary end member 5 and, therefore, a pull upon this rod causes movement of the member 4 toward the stationary member 5 and consequently to frictionally grip the drum by means of the band 3. However, a great number of operations of this type has been found to cause a certain amount of wear upon the band and the retarding action of the band itself upon the drum, is confined to the periphery of the drum. Therefore, there is a tendency that the corner designated 15 of the stationary

member, comes in contact first and consequently it is this portion which will be worn the most. Should there be considerable wear at this point, a pull upon the rod causes the end member 5 to temporarily pivot about the corner 15 since this is naturally the portion which comes in contact first. This pivoting action throws the lower end of the member up and, therefore, throws the band out of engagement with the drum, but the frictional grip of the drum on its opposite side again causes a pull of the band to its face. This action may take place a number of times before the band is in its correct gripping position and is what is termed chatter. In order that this chatter may be overcome, I have provided the cover piece with a screw 13 extending into the slotted portion 10 with its head 17 lowermost. The pull rod 6 being stationary as far as its up and down movement is concerned, the head of the screw 16 is caused to bear on this rod and consequently the corner 15 is held immovable as regards up and down movement with respect to the drum itself. Therefore, should this portion of the end member be worn and my invention applied, the chatter can never be caused because of this wear, for the reason that the screw 16 will prevent up and down movement of the member 5 and consequently its temporary pivotal movement about the corner 15. It is, of course, understood that when my invention is applied to a new device, no unusual amount of wear can be had at this point. A lock nut 18 may be provided to guard against accidental release of the screws 16, or this same screw may be held by a set screw 19, or both may be used if desired. It is essential, however, that some type of locking arrangement be pro-

vided in order that the vibrations may not cause release movement of the screws 16.

What I claim, is:

1. A band brake comprising a drum, a brake band encircling said drum, one end 45 of said band being movable while the other end is held stationary, an end member for the stationary end of said band, an abutment against which said member acts to hold it stationary, an outwardly extending slotted 50 ear for said end member, an operating rod attached to the movable end of said band and adapted to pass through the slot in said end member, and adjusting means for positively limiting the play of said rod up and 55 down in the slot of said member.

2. A band brake comprising a drum, a brake band encircling said drum, one end of said band being movable while the other end is held stationary, an end member for the 60 stationary end of said band, an abutment against which said member acts to hold it stationary, an outwardly extending ear on said member provided with an open ended slot, an operating rod attached to the mov- 65 able end of said band and adapted to pass through the slot in said end member, a cover piece for the open end of said slot rigidly held in position, a screw passing through said cover piece and into said slot and 70 adapted to adjustably bear on said rod to limit its play up and down in said slot, and means for locking said screw in any adjust- ed position.

In testimony whereof I affix my signature 75 in the presence of two witnesses.

ROY M. BROWN.
